UNITED STATES PATENT OFFICE.

JOHN J. MAIER, OF ATLANTA, GEORGIA, ASSIGNOR TO DOWMAN-DOZIER MANUFACTURING COMPANY, OF ATLANTA, GEORGIA, A CORPORATION OF GEORGIA.

SKYLIGHT.

No. 918,876.

Specification of Letters Patent.

Patented April 20, 1909.

Application filed April 17, 1907, Serial No. 368,665. Renewed March 8, 1909. Serial No. 482,174.

To all whom it may concern:

Be it known that I, JOHN J. MAIER, a citizen of the United States, and resident of Atlanta, in the county of Fulton and State of Georgia, have invented certain new and useful Improvements in Skylights, of which the following is a full, clear, and exact description, such as will enable those skilled in the art to which it appertains to make and use the same, reference being had to the accompanying drawings, forming part of this specification.

This invention relates to improvements in skylights in which the frame supporting the lights is made of metal. As generally constructed the members of such frames are joined either by soldering or by riveting. Such structures are not well adapted for fire-proofing purposes, for when subjected to intense heat either the solder melts or the riveting is broken by the expansion of the parts, which causes a collapse.

In the present invention it is proposed to avoid the use of solder or rivets by joining the parts composing the frame by interlocking the different members. By doing this the frame will retain its integrity so long as the metal does not fuse.

The invention consists in the novel construction, combination and arrangement of parts, such as will be hereinafter fully described, pointed out in the appended claims and illustrated in the accompanying drawings.

In the drawings, in which similar reference characters designate corresponding parts, Figure 1 is a perspective view of a section of skylight embodying the invention. Fig. 2 is a cross-sectional view of the same. Fig. 3 is a sectional view on the line 3—3 of Fig. 2. Fig. 4 is a detail perspective view of part of the ridge. Figs. 5 and 6 are detail perspective views of parts of one of the mullions. Fig. 7 is a detail perspective of part of the sill and bottom rail.

The sill A is shaped to form a cap for the curb B on which the skylight is mounted. It comprises the crown 1 resting on the upper edge of the curb and the sides 2 and 3 respectively contacting with the outer and inner faces of the curb. The outer flange 2 is extended a considerable distance below the top of the curb and its lower edge is bent outwardly to form the guard 4, which serves to throw outwardly the drip descending from

the skylight. At the end of the skylight the sheet metal forming the crown 1 of the sill is bent upwardly to form the gable 5. At the corners of the skylight, as at 6 (Fig. 1), the ends of the meeting parts are cut to form tongues, which are interlocked to form the joint.

Resting on the crown 1 of the sill A is the bottom rail C of the sash. The rail and sill are formed from the same piece of sheet metal. At the lower edge of the side 3 of the sill the metal is folded back on itself and extends upwardly to form the brace 7 for the lower end of the sash. At the upper edge of the brace the metal is bent back to form the shelf 8 that rests at its lower edge on the sill 1. There the metal is bent upwardly at right angles to form the base 9 of the bottom rail. The shelf 8 and the base 9 form a trough in the rail extending beneath the lower end of the sash. This trough serves to catch any moisture that may drain from the under surface of the sash. In the base 9 are the vent holes 10 to permit the liquid to escape from the trough to the exterior of the skylight. The upper edge of the base 9 is folded back on itself a short distance, as at 11, and then bent outwardly, as at 12, to form a seat or socket for the lower edge of the light D. At the edge of the part 12 is the locking tongue 13 to engage the lower ends of the mullions to be described farther on.

The ridge E of the skylight is hollow, having a four-sided polygonal shape in cross-section. Its two upper sides 14 and 15 of equal length meet at their upper edges in an obtuse angle and form the crown of the ridge. The two lower sides 16 and 17, also of equal length but longer than the upper sides, meet at their lower edges in an acute angle and form the abutments for the upper ends of the mullions that support the sides of the lights. At the upper and lower edges of each abutment are the ledges 18 and 19 forming the socket to receive the upper ends of the mullions. Between the ledges 18 and 19 are the intermediate flanges 20 and 21 forming the seat for the upper edges of the lights. At the edge of flange 21 is the downwardly projecting tongue 22 to engage the upper ends of the mullions when the latter are in place. In the flange 20 is the socket 23 to receive the tongue 24. In the ledge 18 at the upper edge of the side 17 is the socket 25 to receive the tongue 26.

The ridge E is formed of three pieces of sheet metal, *a*, *b* and *c* respectively. The member *a* is bent to form the crown and ledges 18 and also the upper part of the side 16, including in the latter the flanges 20, 21, and the tongue 22 of that side. The member *b* forms the ledges 19, the lower parts of the sides 16 and 17, and the tongue 24. The member *c* forms the upper part of the side 17, the latter including the flanges 20, 21, on that side and the tongues 22 and 26. When the three members are assembled with their tongues engaging with their respective sockets and the mullions in place, 15 said members are firmly locked together so as to form a stiff, substantial ridge. The latter is secured to the gable 5 by the tongues 27 at the end of ridge passing through the gable and upset on the outside of the same. 20 (Fig. 1).

The mullions F extend from the bottom rail C of the sash to the ridge E. As they are alike in construction, a description of one will suffice for all. At its lower end the mullion rests on the shelf 8 and abuts the base 9 of the bottom rail; at its upper end it abuts the side 16 of the ridge between the ledges 18 and 19 and rests upon the latter. The main part of the mullion is formed of a single piece 30 of sheet metal. At its upper edge is the rib 28 formed by a fold in the metal. This rib fits at its upper end between the flange 21 and the ledge 18 and is slotted, as at 29, to receive the flange 20. At its lower end the 35 rib enters the slot 30 of the seat 12 for the light in the bottom rail. At the lower edge of the rib the metal is bent outwardly at right angles in opposite directions to form the light seats 31. When the mullion is in place these seats 31 are flush with the seat 11 and the flange 21 and form a support for the light D. At the outer edge of each seat 31 the metal is inclined inwardly, as at 32, and then outwardly to form the gutter 33, which 40 projects beneath the side edge of the light. The gutter empties into the trough in the bottom rail C formed by the shelf 8 and the base 9. It serves to collect any drip that may fall from the edge of the light and to 45 conduct it to the trough. At their upper ends the seats 31 project beneath the flange 21 and are slotted, as at 34, to receive the tongue 21. The flange 21 is also slotted, as at 35, to receive the rib 28. At their lower 50 ends the seats extend beneath the seat 12 in the bottom rail C and are provided with the slots 36 to receive the tongue 13. When the mullion is in place and the several engaging parts register with each other it is firmly 55 held in place.

On the main part of the mullion is the clamping bead G that serves to hold the lights in place. It is formed of a strip of metal having a socket 37 shaped to fit 60 tightly the rib 28. Extending outwardly

from the socket part are the flanges 38 having their edges 39 turned downwardly. When the clamping bead is in place its upper end projects beneath the ledge 18 of the ridge E and its lower end extends below the fold 11 70 in the bottom rail C. The flanges 38 project over the adjacent edges of the lights and the downwardly turned parts 39 press on the glass and the lights are thereby held in place. 75

Having thus described my invention, what I claim and desire to secure by Letters Patent is:

1. In a sheet metal sash for skylights, a rail comprising a shelf, a base projecting 80 from an edge of said shelf, a seat for the light projecting from said base, a tongue on the edge of said seat, said seat and tongue having a transverse slot; and a mullion resting on said shelf, abutting said base and comprising a rib at its upper edge engaging the transverse slot in the seat and tongue, and a light-seat projecting from the side of the mullion having a slot to receive said tongue. 85

2. In a skylight, a curb and a sash of sheet 90 metal comprising a sill fitting over said curb, a bottom rail formed of a shelf resting at the lower edge on said sill, a brace extending from said sill to the upper edge of said shelf, a base projecting from the lower edge of said shelf, 95 a mullion resting on said shelf and abutting said base, and an interlocking joint connecting said mullion with said bottom rail.

3. In a sheet metal sash for skylights, a 100 hollow ridge having a side forming an abutment, ledges at the upper and lower edges of said abutment, flanges projecting from said abutment intermediate of said ledges to form a socket for the light, a mullion with its end 105 resting against said abutment between said ledges, and an interlocking joint connecting said abutment with said mullion.

4. In a sheet metal sash for skylights, a 110 bottom rail comprising an inclined shelf, a base projecting upwardly from the lower edge of said shelf and having vent holes adjacent to its lower edge, a seat for the light projecting from the upper edge of said base, a tongue on the edge of said seat, said seat 115 and said tongue having a transverse slot; and a mullion resting on said shelf and abutting said base and comprising a rib at its upper edge engaging the transverse slot in said seat and tongue, a light-seat projecting 120 from the side of the mullion having a slot to receive said tongue, and a gutter at the lower edge of the mullion emptying onto said inclined shelf.

5. In a sheet metal sash for skylights, a 125 ridge provided with an abutting face, ledges projecting from the upper and lower edges of said face, flanges projecting from said face intermediate of said ledges to form a socket for the light and the lower of said flanges pro- 130

vided with a slot; a tongue on said slotted flange; a mullion having an end resting against said abutting face between said flanges comprising a rib slotted at its end to receive the upper of said flanges, seats for the lights on opposite sides of said rib and provided with slots to receive said tongue, gutters below said seats, and a clamping bead on said rib.

10 6. In a skylight, a ridge comprising an abutment, ledges at the upper and lower edges of said abutment forming a socket between them, a flange projecting from said abutment between said ledges to form a light-seat, a tongue on said flange, said tongue and flange having a transverse slot; and a mullion seated in said socket comprising a light-seat flush with the light-seat of the ridge and having a slot to receive said tongue.

20 7. In a skylight, a ridge comprising an

abutment, ledges at the upper and lower edges of said abutment to form a socket between them, upper and lower flanges projecting from said abutment between said ledges to form a light-seat, a tongue on the lower of said flanges, said tongue and lower flange having a transverse slot; and a mullion seated at an end in said socket comprising a rib registering with said slot in the tongue and lower flange and provided with a slot to receive the upper of said flanges, and a light-seat projecting from the side of the mullion flush with the light-seat of the ridge and having a slot to receive said tongue. 25 30 35

In testimony whereof I hereunto affix my signature in the presence of two witnesses.
